UNITED STATES PATENT OFFICE.

EDGAR F. COLLINS, OF SCHENECTADY, NEW YORK, ASSIGNOR TO GENERAL ELECTRIC COMPANY, A CORPORATION OF NEW YORK.

ELECTRIC-RESISTANCE FURNACE.

1,310,060.

Specification of Letters Patent.

Patented July 15, 1919.

Application filed September 21, 1918, Serial No. 255,140. Renewed April 30, 1919. Serial No. 293,810.

To all whom it may concern:

Be it known that I, EDGAR F. COLLINS, a citizen of the United States, residing at Schenectady, county of Schenectady, State 5 of New York, have invented certain new and useful Improvements in Electric-Resistance Furnaces, of which the following is a specification.

The present invention relates to industrial electric resistance furnaces suitable for heat treating large objects, such as guns, engine shafts, large blocks and the like, at temperatures in some cases approximating the softening point of iron.

15 It is the object of my invention to provide a furnace operable at high temperatures which is capable of efficient distribution of heat from the resistor to the work, without local overheating and in which the heating 20 resistor and supporting parts are sufficiently rugged to permit the furnace to be operated under commercial conditions with a long life. My invention comprises a novel arrangement of the heater and support, as 25 will be pointed out with greater particularity in the appended claims.

In the accompanying drawings, Figure 1 is a side elevation, partly in section; Fig. 2 is a horizontal section in part broken away; 30 Fig. 3 is a sectional detail view of the furnace wall showing terminal connections of the heater; Fig. 4 illustrates part of the heating unit and support; Figs. 5 and 7 are sectional views of a modified wall structure; 35 Fig. 6 is a perspective view of a heater support, and Figs. 8, 9 and 10 are detail views of insulators between heater turns to prevent short-circuiting.

Referring to Fig. 1, there is a furnace comprising a casing consisting of a brick wall 1 surrounded by a metal shell 2 of boiler-plate or the like; preferably there is provided a layer 3 of pulverulent heat insulating material between the brick wall and the 45 outer metal shell. The furnace is provided with an inner lining 4 of fire brick, into which are built longitudinally supporting ribs or columns 5 of metal, to which are fastened the frames 6, carrying the heater 7. 50 In some cases the columns supporting the

heater frames are preferably embedded within the lining of the furnace. Such an arrangement is illustrated at 5' in Figs. 5 and 6. The columns 5', as shown in perspective in Fig. 6, are U-shaped, the ends being 55 provided with cross-bars 8 to which the heater frames are attached by bolts 14 (Fig. 7).

As best shown in Figs. 2 and 3, the frames supporting the heater consist of two rows 60 of segmental plates or channel irons 11, 12, circumferentially arranged adjacent the inner fire brick wall of the furnace but spaced away from the wall. The circumferential plates are spaced a short distance apart from 65 each other at their ends to allow room for expansion when the furnace becomes heated. Located between the plates 11 and 12, are spools 13 consisting of refractory insulating materials, such, for example, as 70 alundum. As the frames 11 and 12 are rigidly held together by bolts 14 the insulating spools 13 simply pass through holes in each of the frames 11 and 12 being held in position by their surface configuration, as 75 indicated in the drawing.

Passing over the insulating spools 13 and gravitationally supported thereby is the ribbon-like heater 7, which passes alternately through one set of frames to the other in a 80 vertical direction, or in a direction parallel to the vertical axis of the furnace. This construction enables the heater ribbon to expand at elevated temperatures without coming into contact with any part of the furnace 85 other than the insulating spools and avoid contact between the slackened loops of the heated conductor which would cause part of its length to be short-circuited. The resistor consists of any suitable refractory material, such as for example, an alloy of 64 to 65 parts nickel, 18 to 22 parts chromium, 10 to 16 parts iron and about 1 to 2 parts manganese.

The ends of the heater 7 are fastened by 95 rivets 15, or in any other suitable way to a refractory conductor 16, passing through the furnace wall and provided at their outer ends with conductors 17, fastened by nuts 18 and serving to supply the heating current. 100

The furnace is provided with any desired number of sets of heating resistors. In section in Fig. 1, eight sets of frames, each carrying insulating spools upon which the heating resistor may be wound, are indicated. The furnace preferably is supplied with a cover consisting of a metal shell 20 lined with fire brick 21 and an inner layer of ordinary brick 22. The cover may be provided with a central casting 23 containing a hole or passageway through which cables or chains supporting the work being heat-treated in the furnace may pass.

In some cases a housing consisting of blocks of suitable refractory insulating material may be placed to advantage between the turns of the heater ribbon adjacent the heater frames, as illustrated at 25, Figs. 8 and 9, and in perspective in Fig. 10. Between the blocks 25 and fitting into the notches in the blocks 25 are oblong blocks 26 of refractory insulating material. The main function of these blocks is to prevent accidental short-circuiting between heater turns by particles of conductive material derived from the charge being treated or any other source.

What I claim as new and desire to secure by Letters Patent of the United States, is,—

30 1. An electric furnace comprising a casing, circumferential frames supported at different heights by the inner wall of said casing, refractory insulating members on each of said frames and a looped resistance heater supported at bends by said members and extending between said frames.

2. An electric furnace comprising a casing, a plurality of pairs of circumferential plates attached at different heights to the inner wall of said casing but spaced away therefrom, insulating spools extending between said paired plates and a resistance heater supported by said insulating spools and extending between said paired plates.

45 3. An electric furnace comprising a casing, a circumferential frame attached to the inner wall of said casing, insulating spools attached to said frame and a sinuous resistance heater having a plurality of sections extending longitudinally in said furnace, supported at the bends between said sections by said spools.

50 4. An electric furnace comprising a cylindrical insulating wall, a metal lining for said wall, longitudinal ribs connected to said lining, a pair of circumferential plates connected to said ribs, and radially displaced from each other, a second pair of circumferential plates, longitudinally displaced from said first pair, insulating spools extending radially between the plates of each pair, an electric resistance heater wound back and forth alternately over the spools of said respective paired plates and terminal

conductors for said heater extending through 65 said wall.

5. An electric furnace comprising a vertical casing, a plurality of sets of concentric segmental frames supported at different heights by the inner wall of said casing and spaced away therefrom, insulating spools consisting of refractory material mounted on each set between said concentric frames, a resistance heater supported by said spools and passing alternately from one of said sets of frames to the other to form a series of loops extending vertically in said furnace, conductors of refractory material connected to said heater extending through said furnace casing, and a sleeve of refractory 80 insulating material surrounding said conductors.

6. An electric furnace comprising a casing, circumferential frames within said casing and attached at different heights to said casing, a resistance conductor extending between said frames, insulating supports for said conductor and a protective housing of refractory material located about said conductor adjacent one or both of said frames. 90

7. An electric resistance furnace comprising an inclosing furnace wall, a ribbon-shaped resistor located to radiate heat to a charge within said furnace, current connections for said resistor and means for supporting said resistor adjacent the inner surface of said furnace wall and in position to freely expand and contract out of contact with said wall.

8. An electric resistance furnace comprising a furnace wall, refractory supports mounted upon said wall and projecting away therefrom, a resistance heater having a plurality of bends and being gravitationally upheld at said bends by said supports and current connections for said heater.

9. An electric resistance furnace comprising an inclosing furnace wall having a lining of refractory material, a sinuous ribbon-shaped resistor, current connections therefor, and means for supporting said resistor adjacent the inner wall of said furnace. 110

10. An electric resistance furnace comprising an inclosing furnace structure having a lining of refractory material, and refractory members supported by the wall of said furnace, a sinuous resistor supported at its bends by said members and located to radiate heat to a charge within said furnace and having sections between said bends in substantially a vertical position to permit free expansion and contraction of said resistor when subjected to temperature changes.

11. An electric resistance furnace comprising an inclosure having a refractory lining, refractory supports extending away from said lining, and a refractory resistance heater having a plurality of bends and in-

tervening straight portions upheld by said supports in effective heat radiating relation to a charge-receiving chamber in said furnace.

- 5 12. An electric heating device comprising an inclosure having a refractory lining, refractory supports extending away from said lining, and a refractory resistance heater

mounted upon said supports out of contact with said lining and in direct heat-radiating relation to the heating space within said device.

In witness whereof I have hereunto set my hand this 19th day of September, 1918.

EDGAR F. COLLINS.
